ERNEST L. GALE, SR., OF YONKERS, NEW YORK, ASSIGNOR TO OTIS ELEVATOR COMPANY, OF JERSEY CITY, NEW JERSEY, A CORPORATION OF NEW JERSEY.

CURRENT-CONTROLLING APPARATUS.

1,089,920.

Specification of Letters Patent. Patented Mar. 10, 1914.

Application filed June 11, 1907. Serial No. 378,409.

To all whom it may concern:

Be it known that I, ERNEST L. GALE, Sr., a citizen of the United States, residing at Yonkers, in the county of Westchester and State of New York, have invented a new and useful Improvement in Current-Controlling Apparatus, of which the following is a specification.

My invention relates to apparatus for controlling electric currents, and although herein shown as applied to electric motors, it may have a general application.

The object of my invention is the provision of improved and simplified construction which will consume minimum current during the starting and operation of a translating device controlled by electric current.

Another object of my invention is the provision of means for absorbing the field discharge to prevent sparking or arcing at those points where the continuity of conductors is interrupted.

Other objects of my invention will appear hereinafter.

The accompanying drawing illustrates diagrammatically in a single view, one arrangement for carrying out the objects of my invention. It is obvious, however, that those skilled in the art may make various changes in the details and arrangement of parts without departing from the spirit and scope of my invention as defined by the claims, and I desire, therefore, not to be limited to the precise construction herein disclosed.

Referring to the drawing, 1 designates a motor-armature, and 9 a shunt field circuit therefor connected between the point 14 of the positive main and the point 15' connected to the negative main, so that the shunt field circuit will be connected across the mains when the switch 10 is closed.

4^A, 4^B and 4^C designate sections of starting resistance. The form of the starting resistance will depend upon the nature of the current, that is, whether it is direct, intermittent, alternating, etc. The main armature circuit is shown by the heavy black lines and extends between the + main and the - main, and includes the armature 1, sectional starting resistance and the switch 10.

Connected to the terminals of the sections of the resistances 4^A, 4^B, 4^C, are, respectively, the contacts 5^A, 5^B, 5^C, so that when the resistance-varying members 7^A, 7^B, 7^C are in

engagement with said contacts, the resistances will be short-circuited. These resistance-varying members are carried by and movable with the cores or plungers 8^A, 8^B, 8^C, which are movable in the solenoids 2^A, 2^B, 2^C. 60 The solenoid 2^A is connected between the point 24 and the conductor 23 by the conductor 20. The conductor 23 leads to the manual switch 3 which in turn is connected to the negative main. The solenoid 2^B is 65 connected between the point 25 of the conductor 27 and the conductor 23 by means of the conductor 21. And the solenoid 2^C is connected between the point 26 and the conductor 23 by means of the conductor 22. 70

The series of electro-magnets as shown are preferably so arranged that they will be operated successively to lift their cores when they receive current. This, however, is not of so much importance in this particular 75 arrangement, but it is important that the cores should be allowed to descend in serial or successive order so that the sectional starting resistance may be gradually cut out. In this instance this is accomplished by 80 means of the stop screws 46^A, 46^B, 46^C mounted in fixed supports 47. These stop screws limit the upward movement of the cores so that a less number of ampere turns will be 85 acting on the core 8^C than on the core 8^B, and less on the latter than on the core 8^A.

For the sake of convenience, I may term the circuits including the solenoids 2^A, 2^B and 2^C as controlling circuits in parallel with each other. The solenoid 2^A, when both 90 switches 3 and 10 are closed, is connected in parallel to the entire starting resistance provided all of the resistance-varying members are in their upper positions as shown. At this time also the solenoid 2^B is in parallel 95 to the sections 4^B and 4^C. The movement of the core 8^C and the resistance-varying member 7^C connected thereto, may be timed, if desired, by the addition of a retarding device, as, for example, the dash-pot 17, which 100 permits free upward movement but retards downward movement.

The operation of the invention thus far described may be stated as follows: Assuming that the switch 10 is open and the switch 105 3 closed, and the positive and negative mains disconnected from the source of current supply, the resistance-varying members will be held in their normal or lower positions by the weight of the plungers connected there- 110

to. Short-circuiting paths through the conductors 27 will, therefore, at this time be established. Now if the mains are connected to the source of current supply, as for instance, through the usual two-pole switch, the motor may receive sufficient potential to effect the starting of the same, but preferably the solenoids are of sufficient resistance so that the current permitted to flow at this time will have no appreciable effect upon the motor-armature. Current will now flow from the positive main through the armature 1, conductor 20, solenoid 2^A, conductor 23, and switch 3 to the negative main. It will thus be seen that the armature 1 and solenoid 2^A are connected in series with each other. Current will flow also through the armature 1, resistance 4^A, and solenoid 2^B in series with each other; and also through armature 1, sections 4^A, 4^B and 4^C, conductor 22, and solenoid 2^C in series with each other. The solenoids 2^A, 2^B and 2^C will, therefore, be excited with current to effect the lifting of the resistance-varying members from their initial positions to intermediate positions. This will remove the short-circuiting paths around the sections of the starting resistance. It should also be noted that since the sectional starting resistances are normally short-circuited, each solenoid will receive current from substantially the same conductor at the points 24, 25 and 26, and, therefore, all of the solenoids may pick up their cores substantially at the same time, and, therefore, rapidly, if such operation is desired. It is evident, however, that if the relative position of the core 8^A with respect to the solenoid 2^A is such that the resistance-varying member 7^A is lifted first, the current which flows through the solenoid 2^B is cut down by the resistance 4^A, and if the resistance-varying member 7^B is lifted before 7^C, the solenoid 2^C has its current further reduced by all the sections 4^A, 4^B, 4^C. If it is assumed that the + and - mains as represented are already connected to the source of current supply, then both the switches 10 and 3 should be normally in open position. Then upon closing the switch 3, the electro-magnetic switches will be operated to open positions to place the sectional starting resistance in readiness to be connected in series with the motor-armature in the main armature circuit when the switch 10 is closed. As before stated, when the series of electro-magnets are operated, preferably the armature does not receive sufficient current to start the same, but upon closing the switch 10 the main armature circuit is closed and the armature may start. It will be seen that as soon as the switch 10 is closed, the solenoid 2^C is at once short-circuited, so that substantially no current flows through the latter, and since no retarding influence is exerted by diminishing

current in the solenoid 2^C, an external retarding device, namely, the dash-pot 17, is added as a time element to permit the armature to acquire a higher speed, or such a speed that the counter-electro motive force will be increased. After a short interval, the resistance-varying member 7^C will connect the contacts 5^C to short-circuit the section 4^C and permit more potential to be applied to the motor-armature, thus increasing the current through the latter and causing the same to accelerate to a higher speed. It will be noticed that the short-circuiting of the section 4^C is independent of the increase in speed of the motor, but depends upon the external retarding device 17. This section 4^C may be used for cutting down the starting current to a minimum, that is, letting through less current than is absolutely necessary in starting a predetermined maximum load, the latter current being controlled by the resistances 4^A, 4^B.

While the resistance-varying member 7^C is still out of engagement with the contacts 5^C, the solenoid 2^B is connected across the sections 4^B and 4^C, but when the section 4^C is short-circuited or cut out, then the solenoid 2^B is connected only across the section 4^B. Now after the motor attains a predetermined speed and acquires a corresponding counter-electromotive force, the solenoid 2^B begins to release its core 8^B, and resistance-varying member 7^B connected thereto descends until the section 4^B is short-circuited, when the motor starts to accelerate to still higher speed. It should be noted that when the section 4^B is short-circuited or cut out, the current through the solenoid 2^B is also short-circuited or substantially eliminated. The only solenoid now receiving current is that designated 2^A, and the main armature current flows through the armature and the single sections 4^A. At this time the solenoid 2^A is connected across the section 4^A, and when the counter-electromotive force in the armature increases still further so as to cause the potential across the section 4^A to decrease, the current through the solenoid 2^A will gradually decrease to permit the core 8^A to descend and finally cut out the section 4^A and also the solenoid itself. All the sectional starting resistance is, therefore, cut out and all the solenoids are short-circuited, so that substantially all the current flows through the armature and the shunt field circuit 9. The motor can now attain its maximum speed. The arrangement described is often desirable as it gives a wide variation of the potential on which depends the operation of the controlling circuits including the conductors 20 and 21.

When a controlling apparatus such as described is used in connection with a direct current shunt motor, I prefer to connect an extra field circuit 9^A permanently across the

resistance elements 4^A, 4^B and 4^C, as, for example, between the points 11 and 18. It is evident that when the motor is started and the sectional resistances inserted in the normally open main armature circuit, the extra field 9^A is also inserted, and will, therefore, have an appreciable effect in increasing the starting torque, depending upon the amount of the starting resistance. The main object of the extra field, however, is to absorb the field discharge or "kick" due to the shunt field self-induction, and thus prevent the armature from having its insulation punctured by high potential induced currents. When the current is shut off from the motor to stop it, as by the opening of the switch 10, the extra field circuit will remain closed through the armature resistance or the short-circuiting pairs of contacts. The action here is similar to that of the transformer, the extra field circuit 9^A acting like a short-circuited secondary to reduce the self-induction in the shunt coil 9 which acts as a primary. When the current is cut off from the motor the tendency of the shunt field circuit 9 will be to maintain the current and thus produce an extra current which finds a path through the armature. This circuit is the primary circuit. The extra field circuit being in close proximity to the shunt field circuit and being closed externally through low resistance conductors, will act as a short-circuited secondary. This short-circuited secondary has induced in it a current which re-acts on the primary to reduce the shunt field discharge and, therefore, protect the motor. This arrangement avoids the use of any extra current consuming resistances, switches, etc., which are at present often used and so connected that they consume current at all times when the motor is operated. It will, therefore, be seen that the extra field circuit 9^A not only increases the starting torque, but also protects the motor in stopping, and this with minimum consumption of current, as it is short-circuited, when the motor is under normal operation.

Having thus fully described my invention, what I claim and desire to have protected by Letters Patent of the United States is:—

1. In motor controlling apparatus, the combination with an electric motor, of an electro-magnet connected directly in series with the motor-armature, sectional starting resistance, an additional electro-magnet in multiple with said first-named electro-magnet and connected in series with the motor-armature through a section of said sectional starting resistance, a third electro-magnet in multiple with the first two-named electro-magnets and in series with the motor-armature and the entire sectional starting resistance, a switch operated by each of said electro-magnets to control said sectional

starting resistance, a switch for closing the main armature circuit and short-circuiting the third electro-magnet, and a retarding device for the last-named electro-magnet, the second-named and first-named electro-magnets successively permitting their respective switches to operate successively to gradually cut out the remainder of the sectional starting resistance and to substantially eliminate the current flowing through themselves. 75

2. In a motor controlling apparatus, the combination with a motor-armature, of a shunt field circuit, resistance in series with the motor-armature, a controlling circuit 80 connected across said resistance, means operated by said controlling circuit for varying said resistance, and an extra field permanently connected across said resistance.

3. In motor controlling apparatus, the combination with a motor-armature, of a field winding starting resistance in series with the motor armature, means for controlling said starting resistance, and an extra field circuit connected permanently to 85 said starting resistance to absorb the field discharge of the said field winding when the current thereto is reduced. 90

4. In motor-controlling apparatus, the combination with a shunt motor, of starting resistance therefor, means for controlling said resistance, and an extra field circuit connected to said resistance to effect the absorption of the counter-electromotive force of self-induction in the shunt field 100 when the main line current to the motor is cut off. 95

5. In motor-controlling apparatus, the combination with a shunt motor, of starting resistance therefor, of means for controlling said resistance to cut out the same as the motor accelerates in speed, and to maintain the same cut out while the motor is operating and after the main line circuit thereto is interrupted, an extra field 110 circuit connected to the terminals of the starting resistance to increase the starting torque of the motor, and to substantially absorb the counter-electromotive force of self-induction in the shunt field circuit when 115 the current to the motor is cut off. 105

6. In motor-controlling apparatus, the combination with an electric motor, of starting resistance therefor, a series of electro-magnets, a corresponding series of switches 120 operated by said electro-magnets to gradually cut out said starting resistance and to successively eliminate the current through the electro-magnets, and an extra field circuit connected permanently to the terminals 125 of the starting resistance.

7. In motor controlling apparatus, the combination with a motor armature and its field circuit, of sectional starting resistance in series with the said motor armature, a switch 130

- 4
- in the main armature circuit, a plurality of switches for controlling said starting resistance, controlling circuits in parallel to each other and each containing an electro-magnet operable when energized to open said switches and place the starting resistance in the motor circuit, a switch for the said controlling circuits, and means for operating said first named switch and said controlling circuit switch independently of each other.
8. In a self-starter for electric motors, the combination with sectional starting resistance, of a plurality of switches connected to said sectional starting resistance, and a plurality of electro-magnets one for each of said switches, and a plurality of circuits one for each of said electro-magnets, one of said circuits being in series with some of said resistance, and in parallel to the rest of said resistance.
9. In a self-starter for electric motors, the combination with sectional starting resistance, of switches for controlling the same, a plurality of electro-magnets one for each of said switches, and controlling circuits one for each of said electro-magnets and respectively connected to the terminals of the sections of said starting resistance, and to one end of the resistance.
10. In motor controlling apparatus, the combination with a motor armature and a field circuit, of sectional starting resistance in series with the motor armature, a plurality of switches one for each of said sections, and controlling circuits one for each of said electro-magnets and respectively connected to successive terminals of the sections of said starting resistance, and to one end of the resistance.
11. In motor-controlling apparatus, the combination with a motor armature and a field circuit, of sectional starting resistance in series with the motor armature, a plurality of switches respectively connected to the terminals of the sections of said starting resistance, a plurality of electro-magnets one connected to each of said resistance sections, parallel controlling circuits, the first directly in series with the motor armature and each of the next in series with the motor armature and a portion of the starting resistance.
12. In a self-starter for electro-magnets, the combination with sectional starting resistance, of a switch connected to a section thereof, an electro-magnet for operating said switch, a controlling circuit for said electro-magnet and in parallel with said starting resistance, an additional switch for another section of said starting resistance, an additional electro-magnet for operating said additional switch, and a controlling circuit for said additional electro-magnet in series with said starting resistance.
13. In a self-starter for electric motors, the combination with sectional starting resistance, of a switch connected to one of the sections of said resistance and initially short-circuiting the same, an electro-magnet for operating said switch to open the same and delay the time of re-closing the same, a switch for connecting said electro-magnet across the starting resistance and in series with the motor-armature, an additional switch initially short-circuiting another section of the starting resistance, an additional electro-magnet in series with said starting resistance and connected to said additional switch, a main armature switch connected to short-circuit said additional electro-magnet, and a mechanical device for retarding the re-closing of said additional switch.
14. In motor-controlling apparatus, the combination with a motor-armature and a field circuit, of starting resistance for the motor, and an extra field circuit permanently connected at both its terminals to said starting resistance.
15. In motor-controlling apparatus, the combination with a motor-armature and a field circuit, of starting resistance divided into sections, electric switches connected respectively to the terminals of said sections and initially short-circuiting the same, a series of electro-magnets operatively connected to said switches in circuits parallel to each other, the first circuit being in series with all the starting resistance, the last circuit being directly in series with the motor-armature, and the intermediate in series with a portion of the starting resistance, a switch for closing all the circuits for said electro-magnets to cause the latter to open said switches and insert said starting resistance, a main armature switch for closing the main circuit through the motor armature and said starting resistance and at the same time short-circuiting the first electro-magnet of the series, a mechanical device for retarding the closure of the first switch after being released by the first electro-magnet, and means for effecting the successive operation of the other switches to cut out the starting resistance step by step.
